United States Patent Office

Des. 226,713

Patented Apr. 17, 1973

226,713

MODULAR BATHROOM

Levert Ray Johnson, Milton, Fla., assignor to Holiday-Hut Manufacturing Co., Inc., Milton, Fla.

Filed Jan. 15, 1971, Ser. No. 106,949

Term of patent 14 years

Int. Cl. D23—02

U.S. Cl. D23—49

FIG. 1

FIG. 2

FIG. 4

FIG. 5

FIG. 6

FIG. 7

FIG. 1 is an exterior top plan view of the modular bathroom showing my new design;

FIG. 2 is a cross-sectional view taken substantially along line 2—2 of FIG. 1 facing the vanity and sink, the broken line representation of a commode is for purposes of illustration only;

FIG. 3 is a top plan view thereof with the top being removed for convenience of illustration;

FIG. 4 is a cross-sectional view taken along line 4—4 of FIG. 3 facing the wall opposite that shown in FIG. 2, the exterior of said wall follows the interior contours shown;

FIG. 5 is a cross-sectional view taken along line 5—5 of FIG. 3 facing the rear wall, the exterior of said wall follows the interior contours shown;

FIG. 6 is a cross-sectional view taken along line 6—6 of FIG. 3 facing the front wall; and

FIG. 7 is a perspective view showing the exterior appearance of the top, front and right side.

I claim:

The ornamental design for a modular bathroom, as shown and described.
